UNITED STATES PATENT OFFICE.

MICHAEL G. DOBBINS, OF PHILADELPHIA, PENNSYLVANIA, ASSIGNOR OF ONE-HALF
TO FREDERICK H. SHAW, OF NARBERTH, PENNSYLVANIA.

EMERY-WHEEL DRESSER.

1,395,098.

Specification of Letters Patent. Patented Oct. 25, 1921.

Application filed April 30, 1920. Serial No. 377,879.

To all whom it may concern:

Be it known that I, MICHAEL G. DOBBINS, a citizen of the United States, residing at Philadelphia, in the county of Philadelphia and State of Pennsylvania, have invented new and useful Improvements in Emery-Wheel Dressers, of which the following is a specification.

The invention relates to abrading materials and tools and has for an object to provide a tool for dressing emery and other forms of abrading wheels and surfaces.

The invention comprehends among other features an emery wheel dresser of simple construction and design and in which the bearings supporting the spindle which carries the disks or cutters, can be readily renewed when worn, the dresser also including a novel form of protective hood or cover whose combined functions provide for the reduction of the spindle in the bearings and a covering for the cutters arranged to partially inclose the same preventing the flying particles of emery or dust from striking the operator in the face or lodging in the eye.

In the use of emery wheel dressers, it is well known that the usual form of dresser very quickly becomes worn and unfit for further use until it is provided with a new bearing or spindle for the reason that the flying particles of emery or dust, in the operation of the dresser, readily lodge in the bearings and quickly wear and grind them out.

In my improved form of emery wheel dresser, I provide what I term bearing strips, these strips being supported upon a frame or body of the dresser, so that when one of the bearings formed by the strip, becomes worn, it can be readily replaced by another bearing formed by the strips, by simply advancing the bearing strips on the frame.

In the further disclosure of the invention, reference is to be had to the accompanying drawings, constituting a part of this specification, in which similar characters of reference denote corresponding parts in all the views, and in which,—

Figure 1 is a side elevation of the emery wheel dresser, the dotted lines indicating the open position of the cover or guard.

Fig. 2 is an end view.

Fig. 3 is a horizontal sectional view taken on the line 3—3 in Fig. 1, with some parts 55 in plan, and

Fig. 4 is a vertical transverse sectional view taken on the line 4—4 in Fig. 1, with the bolt in elevation.

Referring more particularly to the views, 60 the numeral 10 indicates a body or frame of the dresser, one end of the frame being fitted into or formed with a suitable handle 11, with the other end of the frame bifurcated to form a fork 12. The forming of 65 the fork provides side pieces 13, each of which has a depending foot or rest 14, provided for the ready disposal of the dresser in position to dress an emery wheel. The usual cutters 15 are loosely arranged upon 70 a spindle 16 and disposed between the side pieces 13 as shown, the ends of the spindle being lodged in two of the apertures 23 in bearing strips 17, Fig. 3, the latter being arranged to slide in grooves 18 in the side 75 pieces 13 and extending longitudinally thereof. A cover or guard 19 is provided and adapted to be normally arranged to partially cover or inclose the cutters 15, said cover having projecting ears 20 which, 80 when the cover is in normal position, extend over the outer faces of the side pieces and act as abutments for the ends of the spindle 16. A cross bolt 21 is arranged to extend through a cross opening 22 in the 85 body 10 and also passes through other opening 23 in the bearing strips 17, this cross bolt 21 also constituting the support for the cover or guard 19 which has cross openings 24 through which the bolt extends, a 90 suitable nut 25 being threaded on the free projecting end of the bolt so that when the nut is tightened up it will secure the bearing strips rigidly to the side pieces and swingingly support the cover as shown. 95

Now assuming that the spindle 16 is carried in the foremost openings or bearings of the bearing strips and said bearings wear out and become unfit for further use, it will be apparent that the cover or guard 19, normally lowered, can, after its sides are sprung upwardly to clear the bearing strips 17, be swung up to expose the ends of the spindle, which can now be withdrawn and the cutters of course removed therefrom. The bolt 105 21 is then removed from the bearing strips

and side pieces and the bearing strips are advanced by sliding them forward on the side pieces in the grooves thereof until the next set of openings or bearings of the strips will be in position to receive the spindle and provide new bearings therefor.

The bearing strips described are preferably made of a fine grade of tool steel, and with a construction of the character described it will be apparent that the life of the dresser will be greatly prolonged and with but very little practice the bearing strips can be readily adjusted to provide new bearings in place of the worn out bearings of a spindle after the dresser has been in use for some time. This construction coupled with the arrangement of the cover or protecting hood which retains the spindle against removal from the bearings when the cover is in normal operating position, presents a construction in emery wheel dressers which is simple, cannot readily get out of order, will effectively perform its function and can be cheaply manufactured.

Having described my invention, I claim— 25

An emery wheel dresser comprising a body bifurcated at its forward end and having a transverse aperture in rear of said bifurcation and alined apertures in the walls of the bifurcation and also having longitudinal grooves in its sides, bearing strips with transverse apertures movably arranged in the said grooves of the body, a spindle removably arranged in said apertures in the walls of the bifurcation and in apertures 35 in the bearing strips, a cutter arranged on said spindle and disposed in the bifurcation, a guard straddling the bearing strips and having side walls arranged at the outer sides of said strips to hold the spindle against 40 endwise movement, and a bolt extending through the body aperture in rear of the bifurcation and also through apertures in the bearing strips and apertures in the side walls of the guard. 45

In testimony whereof I affix my signature.

MICHAEL G. DOBBINS.
